Attorney

UNITED STATES PATENT OFFICE.

CHARLES M. CLARK, OF HAVRE DE GRACE, MARYLAND, ASSIGNOR TO LOCK CLIP AND FOLDER COMPANY, INCORPORATED, A CORPORATION OF MARYLAND.

LOOSE-LEAF COVER.

Application filed February 11, 1924. Serial No. 692,081.

To all whom it may concern:

Be it known that CHARLES M. CLARK, a citizen of the United States, residing at Havre de Grace, in the county of Harford and State of Maryland, has invented certain new and useful Improvements in Loose-Leaf Covers, of which the following is a specification, reference being had therein to the accompanying drawings.

10 The invention relates to loose leaf covers, and has for its object to provide a device of this character formed from preferably a pliable heavy paper, and means for holding detachably a plurality of sheets of paper therein, for instance letters. The device is particularly adapted for holding correspondence and forming a cover for the correspondence so that letters may be easily filed in a letter file.

15 A further object is to provide the cover with spaced apertures adjacent the hinging seam thereof, through which apertures arms of a paper fastener extend and engage the upper sheet of paper within the cover. The other arms of the fasteners engage the outer side of the back of the cover, and the apertures allow the cover to be entirely opened for exposing the letters to view.

20 A further object is to provide removable fasteners adjacent the ends of the cover, either of which fasteners may be easily removed, thereby allowing any of the letters to be entirely exposed to view by folding the letters diagonally towards the fastener which remains in place.

25 A further object is to extend the apertures past the hinging portion of the cover and into the adjacent side of the back of the cover, whereby the connecting arms of the jaws of the fasteners will not interfere with the front and back of the cover opening into position in the same plane.

30 With the above and other objects in view the invention resides in the combination and arrangement of parts as hereinafter set forth, shown in the drawing, described and claimed, it being understood that changes in the precise embodiment of the invention 35 may be made within the scope of what is

claimed without departing from the spirit 50 of the invention.

In the drawing:—

Figure 1 is a perspective view of cover showing the same closed.

Figure 2 is a perspective view of the cover 55 showing the same open.

Figure 3 is a detail bottom perspective view of one corner of the cover, showing the clip jaw engaging the back of the cover.

Figure 4 is a detail sectional view taken 60 on line 4—4 of Figure 1.

Referring to the drawing, the numeral 1 designates the cover, which cover is formed preferably from heavy paper of a flexible type, and is bent upon itself at 2 to form the 65 front cover 3 and the back cover 3^a. The cover is preferably adapted for holding a plurality of sheets of paper 4, for instance letters desired to be kept together, and filed in a conventional form of filing cabinet. 70 Heretofore loose leaf covers have been provided with securing fasteners for letters, which fasteners extend through the cover and through apertures in the letters, however where conventional forms of covers 75 are used, involving fasteners, the letters are mutilated and to remove a letter from the lower portion of the stack of letters, it becomes necessary to remove the upper letters from the fasteners, which involves considerable time. It has also been found where fastener covers are used, the cover sections, which form the front and back of the cover 80 can not be straightened out to a position in the same plane. To obviate this difficulty, 85 the front 3 of the cover is provided with T-shaped apertures 5, through which apertures the arms 6 of the paper clips 7 extend and engage the upper side of the upper sheet of paper 4 within the cover. The loops 8 90 of the clips 7 engage the outer side 9 of the back 3^a of the cover and consequently the paper sheets 4 are securely clamped within the cover as a whole, however the top 3 of the cover may be opened to the position 95 shown in Figure 2, where it will be in the same plane as the back 3^a of the cover and consequently the top sheet 4 of paper is ex-

posed for its entire surface, and if the same is a letter, it may be easily read. It will also be seen that any of the sheets 4 may be pulled from the stack without removing the 5 fastener 7, thereby obviating the difficulty experienced with covers of this character where fasteners are used which extend through apertures in the sheets of paper. The transverse recesses 10 of the T-shaped 10 apertures 5 receive the eyes 10^a carried by the clip arm 6, when the front side 3 of the cover is in closed position.

The apertures 5 are sufficiently long whereby their ends 11 extend beyond the 15 hinging point 2 of the front and back of the cover, and into the adjacent side of the back 3^a of the cover, therefore it will be seen that when the front 3 of the cover is moved to open position as shown in Figure 20 2, the connecting portions 12 of the clips will not interfere with the opening of the cover.

From the above it will be seen that a loose 25 leaf cover is provided which is simple in construction, will positively hold a plurality of sheets of paper therein, in a manner whereby any of said sheets may be removed without disturbing the other sheets, the cover will open entirely, and one wherein upon 30 removal of one of the clips, for instance the lower clip, letters within the file may be folded diagonally towards the remaining

clip, thereby exposing the entire contents of letters in the lower portion of the stack of letters.

35

The invention having been set forth what is claimed as new and useful is:—

1. The combination with a folded loose leaf cover provided with apertures in the front fold, of relatively thin clips carried by the back of said cover, a jaw of each of said clips engaging the outer side of the back of the cover, a jaw of said clips extending through said apertures in the front of said cover, said last-named jaws being provided 40 with enlargements disposed in enlarged portions of the apertures and preventing rearward movement of the clips.

2. The combination with a folded loose leaf cover provided with an aperture in its front, adjacent the fold and enlarged at its inner end to form shoulders, of a relatively thin clip carried by the back of said cover, a jaw of said clip engaging the outer side of the back of the cover, jaws of said clip extending through said aperture in the front of said cover, and members carried by said last-named jaws and cooperating with said shoulders for preventing rearward movement of the clip.

50

In testimony whereof I hereunto affix my signature.

55

CHARLES M. CLARK.
